COMPANY

FLUID-OPERATED RECIPROCATING MACHINE TOOL

Application filed May 9, 1925, Serial No. 29,168, and in Great Britain October 16, 1924.

This invention relates to fluid-operated reciprocating machine-tools, such for example as pneumatic hammers for riveting, chipping, caulking, and such like operations and 5 has particular reference to the construction and arrangement of the valve and its associated parts for automatically controlling the working fluid for the tool. The invention also aims to provide a tool of simple construction and of great durability and efficiency and which can be produced at a greatly reduced cost of manufacture. A further 10 object of the invention is to provide a tool of minimum overall length.

15 According to a primary feature of this invention the reciprocating valve comprises a tubular shell, preferably having a reduced middle portion constituting an annular recess and a core of resilient or shock-absorbing material (for example, india-rubber). Preferably, the end faces of the core are recessed in such manner (for example, cone-shaped) that fluid-pressure acting on the said 20 faces tends to expand the core to form a fluid-tight seal with the tubular shell. The form of the valve after heat-treatment is such that the fibre of the material is longitudinal and therefore in the direction to resist impact which ensures maximum durability.

25 According to another feature of the invention the valve-chest is constituted by a sleeve-like member having ports (for example, radial ports) in its wall arranged to co-operate with ports in the walls of a chamber in which the said sleeve-like member may be also provided with passages in its periphery which are completed by the walls of the chamber. In this manner the passages for the operating 30 fluid are made as short as possible which is very desirable to secure the utmost efficiency.

In order to reduce the over-all length of the tool the handle-portion thereof is according to another feature of this invention recessed to 35 constitute a portion of the working cylinder for the reciprocating piston. The said recess may be provided with a liner which constitutes one wall of an annular fluid-supply passage extending round the recess.

40 According to a feature of the invention there is provided between two parts (for ex-

ample between the handle portion and the cylinder casing) between which a fluid-tight joint is desired, a joint ring composed of fibre or of other packing or jointing material which will enable a close and fluid-tight joint 55 to be obtained.

In order that the invention may be more clearly understood one preferred construction of riveting hammer will now be described, by way of example only with the aid 60 of the accompanying drawings in which—

Figure 1 is a longitudinal central section through the hammer;

Figure 2 is a section on the line 2—2 of 65 Figure 1;

Figure 3 is a section on the line 3—3 of Figure 1 but drawn to a scale twice as large as that of Figure 1;

Figure 4 is a side elevation of a cylindrical block which fits within the valve chest and 70 is also drawn to a scale twice as large as that of Figure 1;

Figure 5 is a section corresponding to that of Figure 1 and illustrating diagrammatically the corresponding parts of Figure 1. 75 In this figure the various ports are all shown in the one plane; and

Figure 6 illustrates a modification of the invention.

Like reference numerals indicate like parts 80 in the several figures.

The following description, referring to the construction illustrated in Figures 1 to 4 can be followed in Figure 5 where similar reference letters are employed. The handle 10 is 85 provided with the usual trigger-controlled throttle valve 11 the trigger of which is shown at 12. The valve 11 admits the driving fluid, for example compressed air, from the main supply conduit 13 by way of a port 14 in the handle to an annular recess 15 formed also in the body of the handle. A liner 16 constitutes the inner wall of the recess 15 and also serves as an extension of the working cylinder to be referred to later. 90

The annular recess 15 communicates with a pair of ports 17 which coincide with similar ports in a joint ring 18 and in the cylinder casing 19.

The joint ring is preferably composed of 100

fibre or other packing or jointing material which will enable a close and fluid-tight joint to be obtained between it and the handle on one side and the cylinder casing 19 on the other side. The material may be such as to be slightly compressible so that the parts on either side can become slightly embedded in it.

The ports 17 in the cylinder casing 19 communicate with an annular groove 20 formed in a valve chest 21. The valve chest comprises a cylindrical block having a central bore 22 extending partially through it and constituting a chamber for a reciprocating valve 23. The block 21 is fixed in a chamber adjacent the working cylinder 24 and conveniently above it. The groove 20 is at the rear end of the block 21 and the latter is formed with ports 25 which, when the valve 23 is in its forward position, place the groove 20 in communication with the interior of the valve chamber, that is the bore in the block 21.

The groove 20 is also in communication with a port 26 (Figures 4 and 5) in the forward end of the valve chamber by way of a longitudinal passage 27 in the periphery of the block 21. The port 26 opens into a portion of the valve chamber which is reduced in diameter and this port is never covered by the valve so that the driving fluid exerts a constant pressure on the forward end of the valve.

A by-pass passage 28 connects the forward end of the working cylinder 24 with the valve chest chamber in the casing 19 and is connected with the valve chamber by means of grooves 29 (Figures 4 and 5) and ports 30 and 31 formed in the valve chest 21.

Conveniently the valve chest is formed with two flats 32 (Figures 3 and 4) in which the ports 30 and 31 are drilled. The ports 30 thus open into recesses bounded at one side by the flats and at the other side by the outer casing 19, and are uncovered by the forward end of the valve 23 when in its rearward position and the other ports 31 are uncovered, when the valve is in its forward position, to communicate with a reduced middle portion of the valve. It will be seen that the flats 32 communicate with the passages 29.

There is an additional port 33 (Figures 4 and 5) connecting the longitudinal passage 27 with the forward end of the valve chamber and this port is uncovered when the valve is in its rear position. Thus, assuming the working piston 34 to be in its forward position and the valve 23 in its rearward position, driving fluid is freely admitted by way of the passage 27, ports 26, 33 and 30 and grooves 29 to the passage 28 leading into the forward end of the working cylinder 24. The piston is thus moved rearwardly. The provision of one or more ports 33 prevents

wire-drawing of the fluid flowing to the front end of the valve, which might occur if only the port 26 were provided.

A main exhaust port 35 is formed in the wall of the cylinder 24 and communicates with a passage 36 leading to the rear of the tool where a number of outlet holes 37 are provided. In the particular example illustrated there are two ports 35 and two channels 36 terminating in two sets of outlet holes 37.

When the rear end of the piston 34 in its backward movement covers the exhaust port 35 the compressed air or other driving fluid trapped in the rear end of the cylinder 24 becomes compressed to such an extent as eventually to overcome the constant pressure acting on the forward end of the valve 23 thus driving the valve forward. It will be seen that the rear end of the cylinder 24 is in communication with the rear end of the valve chamber through a port 38 formed in the joint ring 18. During the travel of the piston 34 rearwardly the forward end of the piston uncovers the ports 35 thus permitting driving fluid which was previously admitted through the passage 28 to escape to atmosphere. The piston, however, continues to move rearwardly due to its momentum.

When the valve is reversed as aforesaid that is moved forwardly to the other end of its stroke from the position shown in Figures 1 and 5, the ports 30 and 33 are closed and admission of driving fluid to the forward end of the cylinder 24 is cut off and the driving fluid is admitted to the rear end through the port 38. The piston 34 is then driven forwardly to strike a blow on the tool 39. When the piston uncovers, by its rear end, the ports 35, driving fluid from the back of the piston suddenly escapes and the pressure on the rear face of the valve 23 drops. The constant pressure acting on the forward face of the valve through the port 26 drives the valve backwardly and the cycle of operations above described is then repeated.

During the forward stroke of the piston 34, driving fluid trapped in the forward end of the cylinder 24 is exhausted through the passage 28, channels 29 and ports 31 to the annular recess formed by the reduced middle portion of the valve. The latter, which is then in its forward position, permits the escape of driving fluid through another set of ports 40 which communicate with one of the exhaust passages 36.

It will be seen in the example illustrated that the valve 23 comprises a tubular shell 41 pressed up from thin sheet metal and filled with a core of resilient or yielding material such as india-rubber. The end faces of the core are recessed so that when the fluid pressure acts on them they tend to expand to form a fluid-tight seal with the tubular shell.

In a modification of the invention, illus-

trated in Figure 6, the handle 10 is in hooked or open form and the fluid supply is taken direct from a passage 140 in the handle direct through the port in the joint ring 18 to the valve chamber without passing through an annular passage round a cylinder extension such as 16. In this case the extension 16 is not bushed as in the example illustrated in Figure 1.

10 Referring to the joint ring it is to be observed that it may be of any preferred material not necessarily of fibre as referred to hereinbefore. For instance, it may be composed of an asbestos-graphite composition; 15 or it may be formed of lead or even of other metal which is not necessarily readily compressible.

The provision of such a joint ring has a considerable advantage in that the machining 20 of the faces of the two parts between which it is disposed need not be carried out with such accuracy as would be necessary if the two parts were to be held together face to face so as to give the required fluid-tightness of the joint between them. Also when 25 the joint ring becomes damaged or worn so that it is no longer sufficiently serviceable to maintain the fluid-tight joint it may be readily replaced, and its replacement is a matter 30 of very small expense. Another advantage is that the faces of the joint ring, when it is made of the material into which the adjacent parts can be somewhat embedded, require no 35 machining and the joint ring can be stamped, moulded, or otherwise formed according to the 40 nature of the material employed.

Although specific forms of the invention 45 have been described in detail it is obvious that modifications in construction may be 50 made, without departing from the invention, according to the type of tool under consideration.

We claim—

1. The combination of a valve chest formed 45 as a tubular sleeve adapted to fit in an outer casing and having in its outer periphery at one end an annular groove whereof one wall is constituted by a flange at said end of the chest, which groove has an admission port 50 connecting it with the interior of the chest, which chest has a recess in its periphery near the other end thereof, a passage for conveying driving fluid connecting said recess with the adjacent end face of the chest, and a port 55 for connecting said recess with the interior of the chest, and a fluid-actuated reciprocatory valve in said chest for controlling said ports, which valve comprises a tubular shell and a core of yielding material in said shell.

60 2. The combination of a valve chest formed as a tubular sleeve adapted to fit in an outer casing and having in its outer periphery at one end an annular groove whereof one wall is constituted by a flange at said end of the chest, which groove has an admission port 65

connecting it with the interior of the chest, which chest has a recess in its periphery near the other end thereof, a passage for conveying driving fluid connecting said recess with the adjacent end face of the chest, and a port 70 for connecting said recess with the interior of the chest, which chest further has a port situated towards the latter end of the chest in a part of its periphery circumferentially remote from said recess, and a conduit connecting said groove with the latter port, and a fluid-actuated reciprocatory valve in said chest for controlling said ports, which valve comprises a tubular shell and a core of yielding material in said shell. 75

3. The combination of a valve chest formed as a tubular sleeve adapted to fit in an outer casing and having in its outer periphery at one end an annular groove whereof one wall is constituted by a flange at said end of the chest, which groove has an admission port 80 connecting it with the interior of the chest, which chest has a flat-bottomed recess in its periphery near the other end thereof, a passage for conveying driving fluid connecting said recess with the adjacent end face of the chest, and a port in the flat bottom of said recess for connecting said recess with the interior of the chest, and a fluid-actuated reciprocatory valve in said chest for controlling said ports, which valve comprises a tubular shell, and a core of yielding material in 85 said shell. 90

4. The combination of a valve chest formed as a tubular shell adapted to fit in an outer casing and having in its outer periphery at one end an annular groove whereof one wall is constituted by a flange at said end of the chest, which groove has an admission port 95 connecting it with the interior of the chest, which chest has a recess in its periphery near the other end thereof, a passage for conveying driving fluid connecting said recess with the adjacent end face of the chest, and two ports connecting said recess with the interior 100 of the chest at the latter end, and a fluid-actuated reciprocatory valve in said chest for controlling said ports, which valve comprises a tubular shell, and a core of yielding material in said shell, which two ports in said recess are arranged spaced apart in the direction of movement of the valve, and one thereof is open and the other closed by the valve in 105 an end position of the latter. 110

5. The combination of a valve chest formed as a tubular shell adapted to fit in an outer casing and having in its outer periphery at one end an annular groove whereof one wall is constituted by a flange at said end of the chest, which groove has an admission port 115 connecting it with the interior of the chest, which chest has a recess in its periphery near the other end thereof, a passage for conveying driving fluid connecting said recess with the adjacent end face of the chest, and two 120

ports connecting said recess with the interior of the chest at the latter end, and a fluid-actuated reciprocating valve in said chest for controlling said ports, which valve comprises a tubular shell, and a core of yielding material in said shell, which two ports in said recess are arranged spaced apart in the direction of movement of the valve, and one thereof is open and the other closed by the valve in an end position of the latter, a conduit in said chest connected at one end to said groove, and another port in said chest connected to the other end of said conduit and opening into the chest at such a position that it is closed by the valve in an end position of the latter when one of the two ports aforesaid is closed, but is opened when that port is opened.

6. For use in a fluid-operated machine-tool, the combination of a valve chest having an admission port at one end and an end wall at the other end, two ports spaced apart in the direction of length of the chest at the latter end, and an exhaust port at the middle of the chest, a fluid-actuated valve reciprocable in said chest in the direction of length thereof, which valve has a recessed middle portion arranged to open communication with said exhaust port and the inner of said two ports, which chest has a conduit that opens at one end into the admission port aforesaid and at the other end is always in open communication with the interior of the chest through a port in the said end wall thereof, which chest further has a port controlled by said valve connecting the end of the chest adjacent the latter port with said conduit.

7. For use in a fluid-operated machine-tool, a valve chest having in its outer periphery at one end an annular groove whereof one wall is constituted by a flange at one end of the chest, which groove has a port connecting it with the interior of the chest, which chest has situated towards the other end thereof an external peripheral recess connected by a passage with the adjacent external end face of the chest, which chest has situated towards the latter end thereof two admission ports opening each into the interior of the chest, one of which latter ports is provided in said recess, which chest further has a conduit in its periphery connecting the other of said admission ports with said groove.

8. For use in a fluid-operated machine-tool, a tubular valve chest having in its outer periphery at one end an annular groove whereof one wall is constituted by a flange at one end of the chest, which groove has an admission port connecting it with the interior of the chest, which chest has situated towards the other end thereof an external peripheral recess connected by a passage with the adjacent external end face of the chest, and two ports connecting said recess with the interior of the chest, which two ports are arranged spaced apart in the direction of length of the

chest, which chest has at the latter end thereof another port opening into the interior thereof outside of said recess, and a conduit connecting the latter port with said groove.

9. For use in a fluid-operated machine tool, a tubular valve chest having in its outer periphery at one end thereof an annular groove whereof one wall is constituted by a flange at one end of the chest, which groove has an admission port connecting it with the interior of the chest, which chest has an end wall closing the other end thereof and has situated towards the latter end a flat-bottomed external peripheral recess connected by a passage that opens into the external face of the adjacent end wall of the chest, which chest has in said recess a delivery port and an exhaust port, spaced apart in the direction of length of the chest, which chest further has at the latter end thereof two other ports spaced apart in the direction of length of the chest, and a conduit in the periphery of the chest connecting the latter ports with said groove, one of which latter ports opens into a recess formed in the inner face of the said end wall of the chest.

In testimony whereof we have signed our names to this specification.

JOHN LEONARD HOLMAN.
ARTHUR TREVE HOLMAN.
